CATHODE RAY OSCILLATOR

Bernard C. Gardner, Philadelphia, Pa., assignor
to Farnsworth Television Incorporated, a cor-
poration of California

Application December 13, 1933, Serial No. 702,141

4 Claims. (Cl. 250—27.5)

My invention relates to a cathode ray oscillator, and more particularly to such an oscillator wherein the beam is collimated with respect to the targets.

Among the objects of my invention are: to provide a cathode ray tube having a collimated beam; to provide a cathode ray tube oscillator in which the beam is collimated with respect to the targets; to provide a means and method for collimating a cathode ray beam; to provide a means and method of regulating the cross section of a cathode ray beam; to provide a means and method of causing a cathode ray beam to diverge in certain directions only; to provide a means and method of predetermining the cross sectional shape of a cathode ray beam, to provide a cathode ray oscillator requiring a minimum of beam deflection; to provide a means and method of regulating the waveform of the output of a cathode ray oscillator; and to provide a highly efficient cathode ray oscillator tube.

Other objects of my invention will be apparent or will be specifically pointed out in the description forming a part of this specification, but I do not limit myself to the embodiment of the invention herein described, as various forms may be adopted within the scope of the claims.

Referring to the drawing:

30 In the drawing which illustrates a preferred form of cathode ray oscillator tube, illustrating the method and a preferred embodiment of my invention, Figure 1 is a longitudinal sectional view, the central portion having been broken away for ease in illustration.

Figure 2 is a cross sectional view taken as indicated by the line 2—2 in Figure 1, but rotated 90° clockwise about the longitudinal axis of the tube for ease of illustration.

40 Figure 3 is a longitudinal sectional view of the target structure taken as indicated by the line 3—3 in Figure 2. This figure has also been rotated 90° clockwise about the longitudinal axis of the tube, as shown in Figure 1.

45 Figure 4 is a cross sectional view of the electron gun only, taken as indicated by the line 4—4 in Figure 1.

Although there are many types of structure known in the art which utilize a cathode ray beam which is moved across a shutter to produce an alternating current, most of these oscillators pay no attention to the shape or relative cross sectional dimensions of the beam. As some of the output energy must be used to move the beam in order that the tube be capable of sustained al-

ternations, it is obvious that the smaller the amount of energy which is needed to move the beam from one of the targets to the next, the more efficient the device will be. Heretofore target spots have been made exceptionally small in order that the movement may be made short, but this has resulted in high electron densities at the point of impact, causing loss by the production of heat in the target. I have found that it is possible to extend the beam over a wide area in one dimension, retaining the other dimension at a minimum. I thus cause the beam to cover a large area on the target, and by causing the rectangular cross section of the beam to be collimated with respect to the division between targets, I am able to get a complete transfer of energy from one target to another with a minimum deflection.

In broad terms, as to the oscillator itself, my invention comprises a pair of targets, and means for generating a cathode ray beam collimated with respect to the division between the targets. My preferred method of collimating the beam, in broad terms, is to apply an accelerating field to a beam of electrons, in which field some of the lines of force are parallel while others are divergent to cause the beam to spread along certain dimensions but not in others. The method, therefore, may be used not only for collimation but also to obtain beams of various odd symmetrical or nonsymmetrical cross sectional shapes. By oscillating beams of various shapes across the division line between targets, it will be obvious that an output waveform of practically any contour desired may be obtained. The apparatus used to shape the beam comprises, in broad terms, an emitter and a perforated anode positioned to accelerate the electrons through the perforation, when energized, the anode being so shaped as to apply a field in which the angles of the lines of force vary circumferentially around the beam.

As an illustration of my invention, I have chosen a cathode ray oscillator wherein the beam is shaped to give a rectilinear spot on a pair of targets, this spot being collimated with respect to a division between the targets. Modification of the apparatus to produce spots other than the rectilinear example here shown will be obvious to those skilled in the art. Referring to the drawing, an envelope 1, preferably of the usual tapered shape having a wide end 2 and a stem end 4 is provided with, at the stem end, a re-entrant stem 5, the inner end of which is closed by a pinch 6. A central grid lead 7 is sealed through the middle of the pinch and supports a

- control electrode 9 which is in the form of a trough opening toward the far end of the tube. On each side of the control lead 7 are cathode leads 10 supporting a filamentary cathode 11 which passes longitudinally through the trough. It is desirable that this cathode be relatively heavy, a good emitter, and not be materially longer than the length of the emitting portion desired. In order, therefore, that the cathode 10 need not be lengthened to extend outside the trough, I prefer to provide the cathode leads 10 with bends 12 so that the joint between these leads and the filament may lie inside the trough if desired.
- 15 Certain filamentary materials do not have a large linear expansion when heated. Others do. When one of the latter materials is used I prefer to break one of the cathode leads and insert in the break a spring 14 bent to take up the slack in the filament when heated, and thus prevent the filament buckling out of its proper position. It is also desirable that the cathode leads be of relatively heavy material having good heat conductivity so that the ends of the filament will not 20 heat to emissive temperature adjacent the junction. In other words, I prefer to confine the heating and consequent emission to the central portion only of the filament, and the length of this emissive portion may be determined by the relative sizes of the filament and the leads to which 25 it is attached.
- Immediately adjacent the emitter I position an accelerating anode 15 supported by anode risers 16 welded to a stem clamp 17. An anode lead 19 passing through the stem seal provides outside electrical connection to the anode. The anode is preferably formed from a plate having a rectilinear aperture 20 therein, the edges of this aperture being provided with longitudinal lips 30 bent and extending toward the filament to form a slit 21 parallel to the filament and in line with the opposite end of the tube. It is desirable that these lips converge slightly so that the slit is somewhat smaller in width than the aperture. 35 Both the slit and the aperture are preferably materially longer than the emissive portion of the filament, the anode being so positioned that the emissive portion of the filament is centrally located with respect to the aperture and slit.
- 40 The wide end of the tube 2 is provided with a pair of targets 22 supported by target leads 24. Each of these targets is substantially of semi-circular shape, positioned so that their straight sides are adjacent, one of the targets preferably being provided with a bend 25 overlapping the straight side of the other target. The division line between the two targets is thus a straight line, and preferably should extend at right angles to the line of the filament and the 45 anode aperture. It is also desirable that the plates have an angular relationship. In the tube illustrated, the plates are positioned to form a right angle, the point of the angle being directed away from the cathode.
- 50 In operation the tube is provided with one or more scanning coils 26, positioned so that their magnetic field, when energized, will deflect the beam from one target to the other. When current is passed through the cathode a short portion in the center of the filament becomes heated and emits electrons. Voltage applied on the anode draws the emitted electrons through the slot 21, to form the beam. Proper tuned circuits 55 may be connected to the targets and a certain amount of the output energy fed through the

scanning coils 26 in such a manner that the beam is continually oscillated across the target division line. An alternating current is thereby produced.

The cross sectional shape of the beam is largely determined by the shape of the anode. In the figures, the path of the beam is shown by the long dash line 27, and the outline of the impact area of the beam by the short dash line 28. It will be noticed that the beam is extended along a line at right angles to the line of the filament and anode slot. Referring to the Figures 1 and 4 which give two sectional views of the gun, it will be noticed, in Figure 4, that electrons leaving the filament are caused to diverge due to the field divergence to the anode lips, and after leaving the anode aperture the beam expands rapidly in the planes at right angles, or normal to the slot. However, as only the central portion of the filament is emissive and the slot and aperture are materially longer than the emissive portion of the filament, there is no tendency to spread the beam longitudinally of the slot. In other words, the lines of force from the edge of the lips nearest to the filament are substantially parallel in the planes parallel with the filament, but are converging in a plane normal to the filament, thus fanning out the beam to have a long dimension at right angles to the filament. As the lips of the anode which form the slot project beyond the emissive portion of the filament, the lines of force are parallel in the plane through the lips and the filament to a point well beyond the emissive portion. It will be noted that the ends of the anode channel are closed by an angle bar 29 in the illustration shown. This bar does not change the field conditions, however, but simply maintains the lips in proper spaced relationship.

It will be obvious that many cross sectional patterns may be produced by following out the methods above disclosed. By changing the angles of the lines of force the beam can be made to diverge more or less in certain directions and not at all in others. The cyclical passage of 4 variously shaped beams across the division line between the targets will obviously produce an output having waveforms related to the shape of the beam. In this manner I have been able to obtain, for example, sawtooth waves having 50 definite angles. Other applications of the methods and apparatus for various purposes will be apparent to those skilled in the art.

I claim:

1. In an oscillator wherein an alternating current is produced by a cathode ray beam of elongated initial cross-section cyclically contacting an adjacent pair of electrodes overlapping to form a single linear division line therebetween, said division line being normal to the long dimension of the initial beam cross-section, the method of operation which comprises spreading said beam to form a spot on said electrodes elongated in a dimension parallel to the division line between said electrodes and normal to the long 60 dimension of the initial beam cross-section, the method of operation which comprises spreading said beam to form a spot on said electrodes elongated in a dimension parallel to the division line between said electrodes and normal to the long 65 dimension of the initial beam cross-section, and cyclically moving said beam from one side of said division line to the other.
2. In an oscillator wherein an alternating current is produced by a cathode ray beam cyclically 70 contacting an adjacent pair of electrodes having a single linear division line therebetween, said beam having an elongated cross-section initially normal to said division line, the method of operation which comprises spreading said beam to 75

form a spot on said electrodes elongated in a dimension parallel to the division line between said electrodes, and cyclically moving said beam from one side of said division line to the other.

5 3. In an oscillator wherein a cathode ray beam cyclically contacts adjacent electrodes having a single, linear, division line therebetween, the method of producing an alternating current which comprises producing said beam with a 10 cross-section elongated normally to the said division line, maintaining the initial length of said beam section normal to said division line, spreading said beam parallel to said division line, deflecting said spread beam normally across said

division line, and collecting said beam alternately upon said electrodes adjacent the line of division.

4. In a cathode ray tube oscillator, the method of operation which comprises generating electrons from a line source, restraining the electrons from diverging in planes parallel to the said source, causing said beam to diverge in planes perpendicular to said source, deflecting said beam cyclically about an axial position after 10 divergence and normal to the direction of such divergence, and collecting said beam during deflection from said axial position.
